DROP HAMMER.

Application filed December 20, 1921. Serial No. 523,606.

This invention relates to drop hammers and has as its object to provide a machine of this character with various features of novelty and advantage, and more particularly to improve the construction so that the board, by means of which the hammer is raised, is given a longer life and is lifted and clamped in a more effective manner.

In the accompanying drawings:

10 Fig. 1 is a front elevation of the entire machine;

Fig. 1^a is a side elevation showing the connection between the foot treadle and the pull rod for the board clamps;

15 Fig. 2 is a side view of the machine in vertical section;

Fig. 3 is a top plan view of the head frame which carries the lifting rolls for the board;

20 Fig. 4 is a top plan view of the board clamp frame and the clamps carried thereby;

Fig. 5 is a horizontal view taken substantially on line 5—5 of Fig. 1;

25 Fig. 6 is a horizontal view in section taken along line 6—6 of Fig. 1.

Figs. 7 and 8 are details.

Referring to the drawings in detail, *a* denotes the base of the machine; *b*, *b*, the uprights adjustably mounted thereon, as hereinafter described; *c*, the head frame mounted on the tops of the standards *b* and carrying the hammer raising mechanism; and *d*, the frame in which the board clamps are mounted. The standards *b* are provided with opposing guide-ways *e* for the hammer *f* to which is secured the board *g*. This board *g*, together with the hammer carried thereby, is raised by means of the hammer raising mechanism including the rolls *h* mounted, as stated, in the head frame, and the board is held in its raised position by the shoes or clamps *i*. The movement of the rolls into and out of gripping relation to the board is controlled through the friction bar *k* by the movement of the hammer. The clamps *i* are controlled by means of a foot treadle *l*.

Referring now more particularly to the construction of the machine, it will be noted, particularly from Fig. 5, that the guide-ways *e* are removably secured in vertical grooves 25 in the opposing faces of the standards *b* by means of bolts 26, the inner

ends of these bolts being secured in place 65 by cross pins 27 and their outer ends being threaded to receive the nuts 28. Preferably, the ways *e* are resiliently held to their seats by springs 29, one about each bolt. This arrangement is of advantage in that 60 when the ways become worn they may be removed from the uprights and their active faces refinished or new ways may be substituted in their place.

In machines of this type, the lives of the 65 boards are usually very short owing to the fact that they splinter and split under the strains and jars to which they are subjected when the hammer is dropped onto the lower die, and also to the crushing strains to which 70 the board is subjected by the lifting rolls and the board clamps. Frequent renewal of these boards is an item of considerable expense, for the boards themselves must be of the best material and therefore costly, 75 and the machine must stand idle during its repair. One of the main objects of the present invention is to provide improvements which result in prolongation of the 80 lives of the boards and to this end the hammer raising mechanism is such that the crushing strains exerted thereby against the board are greatly reduced and heavier hammers can thereby be employed.

In accordance with the present invention, 85 the hammer raising mechanism comprises two sets of rolls, one set arranged above the other, and means for causing the rolls of the two sets to grip the board with substantially like force. In the present illustrative disclosure of the invention, each of the rolls *h* is keyed to a respective shaft 35, and these shafts are journaled in eccentrics 36 mounted for rotation in bearings 37 provided in the upright standards 38 of the 90 head frame *c*. The shafts 35 of the respective sets are connected by gears 39 and are constantly driven by belts passing about the pulleys 40. The eccentrics 36 for each shaft 35 are connected by yokes 42. If desired, one roll of each set, for instance the rear roll, may be fixed against movement to and from the board, while the front rolls are arranged for lateral movement, but preferably the arrangement is such that the rolls of each set move in unison towards and away from each other to grip the board and release it. To this end, in the present in-

stance, corresponding end arms of the yokes for the respective sets of rolls are provided with intermeshing segment gears 43. The corresponding yokes of the two sets of rolls, 5 in the present instance the forward yokes, are so connected to the friction bar *k* that when this bar is dropped the two sets of rolls will exert a like amount of pressure in gripping the hammer board. In the present 10 instance, the friction bar *k* is fixed at its upper end as at 45 to the forward yoke 42 of the lower set of rolls. Connected to this yoke and having sliding movement in an opening through a pin 46 carried by the forward yoke of the upper set of rolls is a rod 47. Between the upper and lower yokes and bearing against the pin 46 is a spring 48. About the upper end of the rod 47 and bearing against the pin 46 is a spring 49, the 15 tension of which may be adjusted by nuts 50. The rod 47 constitutes a link having a loose motion connection with one of the yokes, and the extent of this lost motion is limited by the springs described. The 20 spring 49 is so adjusted that when the friction bar is dropped, the rolls of the upper set will be moved with substantially the same force against the board as the rolls of the lower set.

25 When the friction bar is raised, the action of spring 48 is to withdraw the upper roll from the board thereby insuring that both rolls withdraw substantially together so that the board does not drag on either roll.

30 Such dragging may have the effect of polishing a spot on the board, or else of unduly wearing away the surface and in either case interferes with the lifting action of the rolls by the local change in the friction coefficient.

35 The dropping of the friction bar *k*, which results in moving the lifting rolls into gripping engagement with the board, is controlled by the movement of the hammer on its downward stroke through the knock-off mechanism which is most clearly shown in Fig. 5. The lower end of the friction bar has a sliding movement in a vertical opening through a boss 55 on one of the standards 40 *b* and is provided with a shoulder 56 which is adapted to rest, when the bar is in raised position, on the end of a stop pin 57 slidably mounted in a bore 58 at right angles to the friction bar. This stop pin is adjustably connected by an arm 59 to a knock-off plug 60 mounted for sliding movement in a bore 61 in the standard *b*. The stop pin 57 is normally urged towards the friction bar *k* and the knock-off plug is normally urged to a position where the projecting end thereof extends into the path of movement of the falling hammer by means of a spring 62 housed within the knock-off plug. The projecting end of the knock-off 45 plug is beveled as shown in Fig. 1, and the

side of the hammer is also tapered as at 63 so as to provide a cam surface which wipes against the projecting end of the knock-off plug and forces this plug in when the hammer is dropped.

To accomplish this raising of the friction rod or bar, a sleeve 70 is adjustably connected to it and pivotally carries a resilient arm 71 in the form of a laminate leaf spring the inner end of which is struck by a stud 72 when the hammer is raised. The outer end of the spring 71 is connected by a link 73 to a vertically adjustable bracket 74. It is of advantage to have the arm 71 resilient and more particularly in the form of a leaf 75 spring, as shown, for this arm will then take up the shocks and jars to which it is subjected when the stud 72 hits it and breakage of the parts is obviated. At the same time, the leaf spring possesses considerable 80 strength and is of sufficient rigidity to insure proper operation.

It will be understood that as the hammer falls it releases the friction bar and thereby pressure, derived from the weight of the bar and its connected members, is applied to one of the rolls of each pair of rolls, or to all the rolls as the case may be, causing them to grip the board and raise the hammer until the plug 72 on the latter raises the friction 90 bar, whereupon the rolls withdraw, the hammer falls and the cycle is repeated. This sustained reciprocation continues for as long as the board clamp is held open by the foot treadle.

Referring to Figure 2 it will be seen that the body portion of the hammer is provided with a cylinder 77 in which works a piston 78 connected to a hollow stem 79 which, in turn, is connected to the board *g* as hereinafter 100 described. Leading through the side of the cylinder 77 is a port 80. The space in the chamber of the cylinder 77 above the piston 78 communicates with the atmosphere through a groove 81, pipe 82, a port 83 in the piston and a ball valve 84. Leading from the hollow stem to the periphery of the piston 78 is an oil port 85. It will be seen that with the arrangement described, when the hammer is dropped onto the lower 110 die, the piston 78 which is connected to the board *g*, owing to its inertia, will move downwardly in the cylinder 77 and compress the air in the lower part of this chamber. This air forms a cushion. As the piston 115 thus moves downwardly relative to the cylinder 77, the air will flow past the valve 84 and prevent a vacuum which would otherwise exist in the space above the piston 78. The piston, when the hammer strikes the 120 lower die, will move to the approximate position shown by dotted lines in Fig. 2, and in this position air will flow through the port 80 to the space above the piston. The piston, when it compresses the air in the lower part 125 130

of the cylinder, will tend to rebound but it is prevented from so doing with any jar or shock by the air entrapped above the piston, this air being prevented from flowing past 5 the ball valve as this valve closes with the pressure. When the board is raised, the hammer, owing to its weight, will lag behind the piston so that by the time the hammer reaches its uppermost position, the piston 10 78 is above the port 80 permitting air to again flow into the lower part of the cylinder. While the foregoing cushioned connection between board and hammer is desirable it will be appreciated that it is not 15 necessary to the other features of this invention.

The board is connected to the hammer, in the present instance to the stem 79 thereof, in a very economical yet effective manner as 20 follows. Integral with the stem 79 is an attaching plate 87 having a horizontally extending rib 88 forming the groove 81 between this rib and the top of the stem 79. The ends of the plate 87 have vertical side flanges 25 89 which engage the edge of the board and thus prevent the board from moving in the direction of its width. 90 is a securing plate having a flange 91 at its lower edge adapted to fit in the groove 81. The board is positioned between the plates 87 and 90 and is secured in place by bolts 92 passing through the plates and the board. It will be seen that with this arrangement, the securing plate is interlocked so to speak by the interengaging ribs 88 and 91 against vertical movement relative to the attaching plate 87. Each of the bolts 92 is anchored or supported at each side of the board by the plates 87 and 90.

40 Reference will now be made to the clamping mechanism for holding the board and hammer in raised position, this mechanism being most clearly shown in Figs. 2 and 4. In the present illustrative disclosure, the 45 board clamps *i* of this mechanism are independently adjustable but are operable in unison. Passing through the hubs 95 of each clamp is a pin 96 having eccentric ends 97 eccentrically journaled in eccentric bushings 98 mounted for turning movement in bearings 99 in the upstanding flanges 100 of the frame *d*. The eccentric bushings 98 for each shaft are connected by yokes 101, these yokes including connecting bolts 102. 50 The connecting bolt 102 is received by an elongated slot 103 in the head of a screw 104 adjustably secured to the frame *d* in any suitable manner as by nuts 105. It will be seen that by longitudinally adjusting 55 the respective screws 104, the eccentric bushings 98 will be turned and thus vary the position of the clamping members. The clamping members are moved into and out of engagement with the board so as to grip 60 the same and hold it in raised position and 65 to release it so that the hammer may drop, by turning the eccentric pins 96. In the present instance, these pins are connected by a link 107 so that the pins will rotate in unison and thus simultaneously move the 70 clamping members into clamping engagement with the board or out of engagement therewith, depending on the direction in which the pins are rotated. The pins 96 are rotated in a direction to withdraw the 75 clamps *i* from the board by depressing the foot treadle *l*, this treadle being operatively connected, as shown in Fig. 1^a, to the pull rod 110 which, in turn, is connected at its upper end to an arm 111 extending from a sleeve 112 keyed to the end of one of the pins 96. When the foot of the operator is removed from the treadle *l*, the pull rod of its own weight will fall, and the eccentric pins will be turned in a direction to move the clamping members into engagement with the board so as to hold the same in raised 80 position. In such movement the proximate ends of the clamps slide on the upper face 85 of the board-clamp frame *d*. 90

The uprights or standards *b*, together with the mechanism carried thereby, are adapted to be adjusted transversely of the base *a* of the machine by wedges 125 which are most clearly shown in Fig. 6. It will 95 be seen that the top of the base of the machine is transversely grooved as at 126 and the uprights *b* have a depending web or tongue 127 closely fitting in these grooves. The web or tongue 127 of each standard has 100 an opening 128 therethrough, the inner edge of which is inclined, as shown. The top of the base *a* is also provided with grooves 129 at right angles to the grooves 126 and in these grooves 129 the wedges 125 are positioned. Each of these wedges has on its inner edge a cam surface 130 inclined similarly to and engaging against the inclined edge of an opening 128. The cam surfaces 130 of the two wedges extend in opposite 105 directions and the outer edges of these wedges have a bearing surface against the outside walls of the grooves 129. Threaded into the opposite ends of each wedge are 110 screws 131 the heads of which abut against plates 132. It will be seen that to adjust the uprights, for instance to the left referring to Fig. 6, the forward bolt of the right hand wedge and the rear bolt of the left hand wedge will be loosened and the other two bolts will be tightened up, and then after the standards have been adjusted, the forward and rear bolts for the right and left hand wedges, respectively, will be 115 tightened to hold the wedges in adjusted position. The uprights are further clamped 120 in adjusted position by bolts 133. 125

In order to adjust the lower die and se-

surely hold it in adjusted position relative to the upper die carried by the hammer, a clamping or vise arrangement, shown most clearly in Figs. 1 and 6, is provided. 135 5 designates a shoe adapted to fit in an undercut groove 136 in the anvil portion of the base *a*. 137 is a lower die having a dove-tail tongue 138 fitting in a dove-tail groove 139 in the top of the shoe. 10 As shown in Fig. 6, extending across the opening at the front of the base and supported at its ends against the base is a bar 140. Similarly positioned at the back of the base is a bar 141, and these bars are secured 15 together and held in place by tie rods 142. Carried by the bars 140, 141, and engaging at their inner ends against the ends of the die 137, are adjustable screws 143. It will be seen that with the arrangement described, 20 after the shoe, together with the die thereon, is positioned on the base, the bars 140, 141, are put in place and secured together by the tie bolts 142; then, by turning up the screws 143, the die 137 will be adjusted and held 25 in proper position relative to the upper die carried by the hammer.

The above described relative movement, permitted between the upper and lower rolls provides compensation for a condition in the 30 board which is brought about by the action thereon of the rolls themselves. It will be noted that only the central part of the length of the board is subject to the rolling or squeezing action of both pairs of rolls and 35 that short parts of the board at each end of such central part are subject to the rolling action of only one pair of rolls. This inequality of rolling effect on the board is manifested more especially under sustained 40 rapid reciprocation of the hammer when the differently rolled parts have not a sufficient recovery interval between strokes, and results in slippage of one or both pairs of rolls with consequent misbehavior of the hammer 45 and wear on the board. Correction of the difficulty in the obvious way, as by increasing the gripping pressure, is possible, but not satisfactory, because increased pressure beyond a certain point greatly shortens the 50 useful life of the board, but by giving the upper and lower rolls an opportunity for slight relative movement with respect to each other and while engaged with the board the difficulty referred to is avoided 55 without applying excessive pressure, and thereby sustained reciprocation is rendered possible with hammers of much greater weight than heretofore used in board drop-hammers. It will be seen therefore that the 60 principle of this invention contemplates broadly the provision of relative motion between one of the rolls of each of the sets of board-lifting rolls whether provided by the particular spring arrangement shown in 65 the drawing or equivalent mechanism hav-

ing the same purpose and tending to compensate the conditions referred to.

As a means of keeping the friction surface of the board uniform from end to end, that is to say, with substantially the same friction coefficient at all points, this invention provides for the location of the board clamp below the lowermost pair of rolls, where it normally engages a part of the board which is never in contact with the rolls, thereby avoiding any disturbance of the friction surface which might, have the effect of temporarily overloading one of the pairs of rolls and thereby causing slippage and improper hammer action.

It will be understood that the compensating movement of one of the rolls of the upper set, relative to one of the rolls of the lower set, above referred to, need be merely sufficient to permit said rolls to move in 85 slightly different amount into pressing engagement with the board surface, the pressure being produced by the weight of the friction bar and its connections, as above pointed out, and transmitted substantially 90 equally to the upper and lower rolls.

What we claim is:—

1. In a drop-hammer, a frame, a hammer suitably guided therein for reciprocating vertical motion, a board secured to said 95 hammer, a plurality of lifting rolls spaced apart longitudinally of said board, and means for bringing said rolls into gripping engagement with said board, said means including a compensating connection between 100 said rolls permitting them to accommodate themselves to grip said board.

2. A board drop-hammer comprising the combination with the hammer and hammer board, of a plurality of pairs of driven lifting rolls for the latter, pressure-applying mechanism for said rolls automatically controlled by the hammer to produce sustained hammer reciprocation, and means for permitting relative compensating movement between 105 a roll of one of said pairs and a roll of another of said pairs.

3. A board drop-hammer comprising, in combination with the hammer and hammer board, a plurality of pairs of driven lifting 115 rolls for the latter, pressure-applying mechanism for said rolls automatically controlled by the hammer, means for permitting relative compensating movement between a roll of one pair and a roll of another pair, and 120 a board clamp placed below said rolls.

4. A board drop-hammer including a board-supported hammer, a plurality of pairs of driven lifting rolls, pressure-applying mechanism connected with a roll of each 125 pair for pressing them against the board, means whereby the reciprocation of the hammer automatically actuates and releases said mechanism to produce sustained hammer reciprocation and means included in 130

said pressure-applying mechanism for permitting relative movement between said rolls.

5. A board drop-hammer including a board-supported hammer, a plurality of pairs of driven lifting rolls, pressure-applying mechanism connected with a roll of each pair and adapted for moving them toward and withdrawing them from the board, and means included in said mechanism for permitting relative movement between said rolls, and hammer-operated means for controlling said mechanism to produce sustained hammer reciprocation.

15. 6. A board drop-hammer including a board-supported hammer, a plurality of pairs of driven lifting rolls, a friction-bar connected to impart its weight to one roll of each of said pairs, for pressing them against the board, means in said connection permitting relative movement between said rolls and means on the hammer for automatically raising and releasing said friction bar.

25. 7. A board drop-hammer including a board-supported hammer, a plurality of pairs of driven lifting rolls, hammer-controlled mechanism connected with a roll of each pair for pressing them against and withdrawing them from the board, and a spring associated with one of the rolls permitting compensating movement thereof relative to the other.

35. 8. A board drop-hammer including a board-supported hammer, a plurality of pairs of driven lifting rolls, pressure-applying mechanism connected with a roll of each pair for pressing them against the board, the connection with one of said rolls being yielding and means whereby the reciprocation of the hammer controls said mechanism to produce sustained hammer reciprocation.

45. 9. A board drop-hammer including a board-supported hammer, a plurality of pairs of driven lifting rolls, a friction-bar connected to, and permitting relative movement between, one roll of each pair, means whereby the hammer releases and raises said friction bar to move said rolls toward and from the board and means insuring conjoint withdrawal of both said rolls from the board.

55. 10. A board drop-hammer including a board-supported hammer, a plurality of pairs of driven lifting rolls, pressure-applying mechanism connected to one roll of each pair for pressing them against the board and permitting relative movement between them, a spring (48) adapted to act on one of the rolls to withdraw it from the board, and means for controlling said pressure-applying mechanism to produce sustained hammer reciprocation.

65. 11. A board drop-hammer including a

board-supported hammer, a plurality of pairs of driven lifting rolls, mechanism adapted for applying substantially the same amount of pressure to one roll of each of said pairs and permitting relative movement between said rolls, and means associated with the reciprocating hammer for automatically causing said mechanism to move said rolls toward and from the board.

70. 12. A board drop-hammer including a board-supported hammer, in combination with the hammer and hammer-board, a plurality of pairs of driven lifting rolls for the latter, one of the rolls of each pair being journalled in an eccentric support, an arm on each of said eccentric supports, mechanism for applying pressure to said arms including means for permitting relative movement therebetween, and means whereby the hammer controls said mechanism.

75. 13. In a drop-hammer, a frame, a hammer suitably guided therein for reciprocating vertical motion, a board to which said hammer is secured, two pairs of lifting rolls arranged one above the other, eccentrics in which said rolls are journalled, and means for turning said eccentrics to move said rolls into and out of gripping relation to said board and including an equalizing connection between the eccentrics of the two pairs of rolls whereby the same grip the board with substantially like force.

80. 14. In a drop-hammer, a frame, a hammer suitably guided therein for reciprocating vertical motion, a board to which said hammer is secured, two pairs of lifting rolls arranged one above the other, eccentrics in which said rolls are journalled, a yoke connecting the eccentrics for each roll, a friction bar connected to one of said yokes, a rod connected to said last mentioned yoke and having sliding relation to the yoke connected to the eccentrics for a roll of the other pair, and oppositely acting springs carried by said rod and bearing against said last mentioned yoke.

85. 15. In a drop-hammer, a hammer guided for reciprocating vertical motion, a securing plate connected thereto, an attaching plate, interlocking portions on said plates for preventing relative vertical movement therebetween, a board interposed between said plates, and means for holding said plates against said board.

90. 16. In a drop-hammer, a hammer guided for reciprocating vertical motion, a securing plate connected to said hammer and having a horizontally extending groove, an attaching plate having a portion closely fitting in said groove, a board, the lower end of which is interposed between said plates, and tie bolts passing through said plates and board.

95. 17. In a drop-hammer, a hammer guided for reciprocating vertical motion, a securing plate connected to said hammer and having

a rib forming a groove therebeneath, a securing plate having at its lower edge a flange fitting in said groove, a board, the lower end of which is interposed between said plates, and tie bolts passing through registering openings in said plates and board.

18. In a drop hammer, a hammer provided with a lifting means, a friction bar associated with said means, a laminate spring lever carried on said friction bar and a member on the hammer adapted to engage said spring lever to move the bar and release the hammer.

19. In a drop-hammer, a frame, a hammer guided therein for reciprocating vertical motion and having a stud, lifting means for said hammer, a friction bar associated with said lifting means, a sleeve on said friction bar, a leaf spring carried by said sleeve, and a link between one end of said leaf spring and frame, the other end of said leaf spring being in the path of travel of said stud.

20. In a drop-hammer, a frame including a base, a pair of uprights thereon, a hammer guided in said uprights for reciprocating vertical motion, and means for adjusting said uprights laterally of said base and including a pair of oppositely acting wedges positioned in said base and engaging the respective uprights and screws one at each end of each wedge and within the base for adjusting the same.

21. In a drop-hammer, a base, a pair of uprights arising therefrom, a hammer guided in said uprights for reciprocating motion, a pair of wedges carried by said base and having their opposed edges similarly inclined to form cam surfaces, said cam surfaces engaging against the respective uprights, and means at each end of each wedge and within the base for longitudinally adjusting said wedge and holding it in adjusted position.

22. In a drop-hammer, a base, a pair of uprights arising therefrom, a hammer guided for reciprocating vertical motion in said uprights, said base having beneath each upright a transverse groove and a longitudinally extending groove intersecting said transverse groove, said uprights having tongues fitting in said transverse grooves and openings through said tongues with their inner edges longitudinally inclined in similar directions, a wedge fitting in each longitudinally extending groove and having a cam surface engaging the inner edge of the respective openings in said tongues, and screws one in threaded engagement with each end of each wedge within said longitudinal grooves and anchored against longitudinal movement relative to said base.
